Primary Examiner — Dana Meyrow(74) *Attorney, Agent, or Firm* — David Duckworth(57) **CLAIM**

The ornamental design for a connectable beverage bottle, is shown and described.

DESCRIPTION

FIG. 1 is a top, left, front perspective view of the connectable beverage bottle of my design;

FIG. 2 is a top, rear, right perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof;

FIG. 8 is a bottom plan view thereof;

FIG. 9 is an environmental top, rear, left perspective view of the connectable beverage bottle in a connected condition;

FIG. 10 is an environmental right side elevation view of the connectable beverage bottle in cross-section taken along the line 10-10 in FIG. 7 and shown in a connected condition; FIG. 11 is an environmental top, rear, left side perspective view of the connectable beverage bottle adjacent to a mounting bracket;

FIG. 12 is an environmental top, rear, left side perspective view of the connectable beverage bottle in a connected to a mounting bracket; and,

FIG. 13 is an environmental top, rear, right perspective view of the connectable beverage bottle affixed to a human being using a mounting bracket.

The broken lines shown represent unclaimed subject matter and form no part of the claimed design.
